[57] CLAIM

The ornamental design for a wall mountable non-disposable razor holder, as shown and described.

DESCRIPTION

FIG. 1 is a top plan view of a wall mountable nondisposable razor holder showing my new design;

FIG. 2 is a front elevational view thereof;

FIG. 3 is a left side elevational view thereof, with the razor illustrated in dotted lines for illustrative purposes only, the opposite side being a mirror image thereof; and

FIG. 4 is a front, top and left side perspective view thereof.

The rear and bottom are plain and unadorned.

FIG. 1

FIG. 4

UNITED STATES PATENT AND TRADEMARK OFFICE
